(57) CLAIM

The ornamental design for a midfoot support, as shown and described.

DESCRIPTION

FIG. 1 is a top, front perspective view of a midfoot support, showing my new design;

FIG. 2 is a top plan view of the midfoot support of FIG. 1; FIG. 3 is a front, right elevational view of the midfoot support of FIG. 1;

FIG. 4 is a right side elevational view of the midfoot support of FIG. 1;

FIG. 5 is a rear elevational view of the midfoot support of FIG. 1;

FIG. 6 is a left side elevational view of the midfoot support of FIG. 1; and,
